ELECTRIC WALL SWITCH

Donald L. McFarland, Stratford, Conn., assignor
to General Electric Company, a corporation of
New York

Application March 22, 1952, Serial No. 19,008

Term of patent 14 years

(Cl. D26—13)

To all whom it may concern:

Be it known that I, Donald L. McFarland, a citizen of the United States, residing at Stratford, in the county of Fairfield, State of Connecticut, have invented a new, original, and ornamental Design for an Electric Wall Switch, of which the following is a specification, reference being had to the accompanying drawing forming a part thereof.

In the drawing, Fig. 1 is a front elevation of the wall switch; Fig. 2 is a side elevation view of the wall switch shown in Fig. 1; while Fig. 3 is an end elevation of the wall switch shown in Fig. 1.

The dominant features of my design are shown in the full-line portions of the drawing.

I claim:

The ornamental design for an electric wall switch, substantially as shown and described.

DONALD L. McFARLAND.
